EDGAR GEYER INVENTOR.

BY

Emil F. Langer ATTORNEY

UNITED STATES PATENT OFFICE.

EDGAR GEYER, OF SILVER CREEK, NEBRASKA.

DETACHABLE, SWINGING, WASHBOILER APRON.

Application filed September 21, 1922. Serial No. 589,591.

To all whom it may concern:

Be it known that I, EDGAR GEYER, a citizen of the United States, residing at Silver Creek, in the county of Merrick and State 5 of Nebraska, have invented certain new and useful Improvements in Detachable, Swinging, Washboiler Aprons, of which the following is a specification.

My invention relates to detachable, swinging wash boiler aprons of the kind used to catch and to drain the water which would otherwise drip on the stove, either while transferring clothes to or from the boiler or while dipping water out of or into the boiler, 15 and among the objects of my invention are the following:

To make the apron out of one piece of sheet metal to avoid the cost of welding, riveting or otherwise uniting separate pieces of 20 metal.

To further reduce the cost by cutting out the blanks in such form that the waste of material will be reduced to the minimum.

To eliminate entirely all sharp and rough 25 corners which might tend to catch and tear the clothes.

To make the apron in such form that it can be instantly attached to or detached from a wash boiler or other similar container 30 of clothes.

To make the apron swinging so that it can be readily swung out of operative position against the side of the wash boiler and as readily swung into position with its outlet 35 draining into a pan or other receptacle.

To make the apron in such a form that a number of aprons may be nested to occupy the least amount of space in storage and 40 shipping.

Having in view these and other objects which will appear in the description, I will now refer to the drawings, in which—

Figure 1 shows the apron in its operative position, attached to a wash boiler and draining 45 into a pan.

Figure 2 is a top plan view of the wash boiler with the apron attached.

Figure 3 is a face view of the apron.

Figure 4 is an edge view of the apron, 50 looking from the line 4—4 of Figure 3.

Figure 5 shows a section on the line 5—5 of Figure 3.

Figure 6 is a detail showing the rear side of the apron at one of its lower corners.

Figure 7 is a sectional view of the wash

boiler, lid, and apron, the lid being in place and the apron suspended from the edge of the boiler.

Figure 8 is a sectional view similar to Figure 7, but with the lid removed and the 60 apron in its operative position.

Figure 9 is a detail showing in section the lapped edges of the apron.

Figure 10 is a fragmental plan showing a modification of the upper corners of the 65 apron.

In the drawings the numeral 10 refers to the wash boiler and 11 refers to its lid. Such wash boilers are standardized in size and design, so that it is very seldom that a 70 boiler is found which varies from the standard. The opening of the boiler has two parallel sides and two semi-circular ends. My apron is designed to extend entirely across the straight portion of the side and 75 overlap a portion of the curve at each end. For the purpose of adapting the apron to swing on the upper edge of one of the sides of the boiler, I have curved that portion of the upper edge of the apron which rests on 80 the straight portion of the upper edge of the boiler.

The specific curve employed is substantially that shown at 12 in Figure 5. It is obvious however that the curved portion 12 can not extend over or onto the curved 85 edge of the boiler, as such construction would absolutely prevent swinging of the apron. To obviate this difficulty, I have provided ears 13 which overhang the curved portions of the edge of the boiler. When the apron 90 is in the position shown in Figure 8, the ears will project slightly into the boiler, but when the apron is in its suspended position as shown in Figure 7, the ears 13 will rest on the upper edge of the boiler.

It should 95 here be noted that when the apron is suspended, the curved portion 12 will be flush against the rolled edge of the boiler, where it will not interfere with the lid of the boiler.

At the same time the ears 13 will be 100 in horizontal position between the flange of the lid and the rolled edge of the boiler where they too will not interfere with the lid.

The sides of my apron converge toward 105 the bottom. At each of the side edges is an upstanding flange 14. The flange 14 is double as shown in Figure 9, being thus formed by twice rolling the outer edges of the blank. This construction reinforces 110

the entire apron, but it also leaves no cut edge exposed where it can catch and tear the clothes.

The bottom edge of the apron is lapped 5 on the under side at 15, as shown in Figures 5 and 6. By means of this construction I avoid the exposed cut edge which would otherwise make trouble at the bottom. In 10 one of the lower corners of the body of the apron I punch an aperture 16. By punching this aperture adjacent the overlapped edge 15, or partly in the edge 15 as shown, the edge 15 serves as a reinforcement for the edge of the aperture at the 15 point where the wear occurs.

As before stated, nearly all of the boilers on the market are of a standard size and form, and the only departure from the standard is in the few instances of larger size. 20 It is obvious that the apron made for the standard size would not swing properly on the larger size, owing to the interference of the ears 13. For this reason I have designed a modification of my apron. This 25 modified form of my apron is made without ears, the corner of the apron appearing as shown in Figure 10. This form of apron will function with all commercial wash boilers, in either standard or larger sizes. 30 Of course the same result may be obtained by cutting off the ears from the apron shown in Figures 1, 2, and 4.

In use the boiler and pan are arranged as 35 shown in Figure 1 and my apron is hooked over the upper edge of the boiler with its lower edge resting on the edge of the pan. The arrangement is so simple that it requires only an instant to set it up or to take it down. In transferring wet clothes to or from the 40 boiler, they are passed over the body of the apron which thus catches all of the dripping water and drains it into the pan. Boiling soap suds may be dipped out of the pan and poured into the boiler without spilling a 45 drop. The swinging feature of my apron

facilitates quick change when it is desired to remove one pan and to substitute another. When boiling the clothes the apron is left suspended as shown in Figure 7 with the boiler lid in place. In this way the apron 50 is always in a convenient position where it can not be misplaced under a pile of clothes. When through with the work of washing, the apron may be hung on a conveniently located hook in the laundry, the aperture 16 55 being designed for this purpose.

This application is a continuation in part of my prior application, Serial Number 498,536, filed September 3, 1921. The structure herein described was invented by me 60 before filing my prior application, but important features of the structure were inadvertently omitted from my prior application.

Having thus described my invention and its uses, what I believe to be new and desire 65 to secure by Letters Patent of the United States is:—

An apron for wash boilers comprising a flat sheet metal body portion having converging opposite lateral edges, the wider end 70 of said body portion having a short extension adapted to engage across the upper edge of a wash boiler, said extension being curved to provide a flange adapted to seat over the upper edge of the wash boiler and to present a rounded deflecting head for preventing the catching thereon of articles being removed from the boiler and the displacement of the apron when in use, said curved flange extending from one curved 75 end of the boiler to the other and terminating in ears which are substantially perpendicular to the plane of the body portion of the apron, said curved flange and ears also being adapted to suspend the apron against the side wall 80 of the boiler when not in use and to engage between the body and the cover of the wash boiler when not in use.

In testimony whereof I affix my signature.
EDGAR GEYER.
